UNITED STATES PATENT OFFICE

2,528,846

PRESSING IRON HOLDER

Peter A. Sitnick, Sunland, and Audy W. Christopher, Los Angeles, Calif.; said Sitnick assignor to Clifford B. Howell, Los Angeles, Calif.

Application January 23, 1950, Serial No. 140,126

3 Claims. (Cl. 248—117.2)

1

This invention relates to holders for electric pressing irons and the primary object is to provide an improved device, part of which may be placed on the ironing table as a support for the iron when it is momentarily at rest and which may be secured to another part supported on the wall for storage for a longer period when the iron is not in use. Another object is to provide a storage support part of which may be carried by means of the iron and put in place on the ironing board when it is desired to again use the iron, this part serving as an iron stand during short periods of non use of the pressing iron. A further object is to provide an iron holder which is readily adjustable to irons of different length and which holds the iron only at the edges of the shoe, thus avoiding marring of the iron's polished surfaces.

These and other objects are attained by our invention which will be understood from the following description, reference being made to the accompanying drawing which forms a part hereof, in which:

Figure 1 is a front elevational view of the iron stand as supported on the wall rack;

Figure 2 is a side elevational view of the same;

Figure 3 is a cross-sectional view taken on the line 3—3 of Figure 1;

Figure 4 is a cross-sectional view taken on the line 4—4 of Figure 1;

Figure 5 is a cross-sectional view taken on the line 5—5 of Figure 1;

Figure 6 is a cross-sectional view taken on the line 6—6 of Figure 1;

Figure 7 is a cross-sectional view taken on the line 7—7 of Figure 1;

Figure 8 is a cross-sectional view taken on the line 8—8 of Figure 1; and

Figure 9 is a perspective view showing the iron holder disengaged from the wall rack in horizontal position as a rest for the iron on the ironing board.

In general, our invention consists of a pressing iron stand or support and a wall rack upon which the stand and iron are at times supported and mounted for storage.

Referring to the preferred form shown in the drawings, our invention consists of an iron stand 11 consisting of a metal base plate 12 shaped to conform to the conventional rounded wedge shaped pressing surface of a flat iron or a pressing iron, the metal base plate being covered by a sheet of asbestos board 13 or equivalent heat insulating and non scratching material. The

2

metal base plate 12 is provided on both sides near the point of the iron with flanges 14 which are adapted to engage the edges of the shoe of the iron, these being placed at an intermediate position between the point of the iron and the position of the maximum width of the iron shoe so that the stand may upon occasion be held on the shoe of the iron which wedges into the flanges when both are held in substantially vertical position and in which position the stand may be carried on the iron in conveying it to and from the wall rack 18. The flanges are preferably lined on the inside with an asbestos covering 15 which may be integral with the asbestos plate 13 or may be separate, being adhesively attached to the inside faces of the flanges. Small turned up tabs 14A are also conveniently provided at intervals around the periphery of the metal base plate 12 to more securely hold the asbestos 13 in place, these tabs terminating below the top surface of the asbestos sheet. The base plate 12 is also provided with dimples 16 extending from the face not covered with asbestos, that is, the underside, these serving as resting points for the stand, particularly when it is used in the horizontal position, thus raising the metal plate above the ironing board surface to allow for air cooling. The iron stand 11 is also provided on the underside or uncovered side near the point with a button 17 which serves the dual purpose of raising the front end of the iron stand 11 above the surface on which it rests as do the dimples 16 and of providing attachment means which fits into a slot in the mounting rack as will be later described.

The rack 18 is adapted to be supported in a vertical position on the wall or other vertical surface, screw holes 19 being provided near the upper and lower edges for this purpose. The rack 18 generally consists of an elongated metal plate 20 which is turned outwardly at the lower end to form a shelf 21 upon which the rear edge of the blunt end of the pressing iron may rest. The shelf 21 is preferably provided on its flat iron contacting surface with a sheet of asbestos 22, which is adhesively attached to the surface of the shelf. Reinforcing ribs 23 are also preferably provided in the shelf portion and adjoining vertical portion of the metal of the rack 18. Hooks 24 are conveniently provided below the shelf for holding the cord of the electric iron, these being formed from punched out strips from the metal back of the rack. In the upper portion of the plate 20, there is provided a vertically disposed slot 25 having a tapered guide 26 at the

upper end adjacent an opening 27 which is large enough to receive the button head 28 of the button 17. The stem 29 of the button 17 is adapted to slide in the slot 25, the head 28 holding the iron stand against the plate 20 of the rack and preventing the stand and the iron engaged in the flanges thereof from falling from the rack when the iron is resting on the shelf.

The manner of using my iron stand rack will be apparent from the above description. As a support for the iron while in use on the ironing board, the iron stand is used in the horizontal position, the dimples 16 and the button 17 acting to space the metal plate 12 from the ironing board surface. The iron is temporarily rested on the asbestos surface during interruptions of the ironing operation. When it is desired to discontinue ironing and storing the pressing iron, the pointed end of the pressing iron is advanced forwardly on the stand until the flanges 14 engage the edges of the shoe. The iron stand may thus be raised to a vertical position while it hangs attached by the flanges. With the rest supported on the (hot) iron, the button 17 is then inserted through the opening 27 with the help of the tapered guide 26 into the slot 25 and the rear or blunt end of the pressing iron is allowed to come to rest on the sheet of asbestos 22 on the shelf 21, the iron stand remaining in contact with the pressing iron through the flanges 14. The pressing iron is thus securely and safely stored without danger of fire or without danger of the iron falling. The elongated slot 25 permits the use of the iron stand and rack for various sizes or lengths of pressing irons and the flanges 14 are adaptable for engaging the pointed end portion of irons of conventional shape and of the ordinary range of sizes. Our device is inexpensive to manufacture, is simple and convenient to use, and provides safe storage for a hot pressing iron while cooling, and after cooling.

We claim:

1. A pressing iron holder comprising an iron stand for supporting the pressing iron while in use on the ironing board, and for use in supporting the iron on a wall rack, and a wall rack adapted to be attached to a vertical surface for supporting the pressing iron and the stand during storage, said iron stand comprising a base plate shaped to conform to the conventional rounded wedge-shaped pressing surface of the iron, said plate being provided with opposed turned up-and-over flanges adjacent the iron point adapted

to engage the shoe of the iron, said base plate being also provided with spacing dimples and a headed button projecting from the underside of said plate; and said wall rack comprising shelf means upon which the blunt end of said iron may rest, while engaged by said flanges of said iron stand, and means for adjustably securing said iron stand in vertical position on said rack.

2. A pressing iron holder comprising an iron stand for supporting the pressing iron while in use on the ironing board, and for use in supporting the iron on a wall rack, and a wall rack adapted to be attached to a vertical surface for supporting the pressing iron and the stand during storage, said iron stand comprising a base plate shaped to conform to the conventional rounded wedge-shaped pressing surface of the iron, said plate being provided with flanges adjacent the iron point adapted to engage the shoe of the iron, said base plate being provided with a headed button projecting from the underside of said plate; and adapted to be engaged by a vertical slot in said wall rack; and said wall rack comprising a back plate with a turned-out shelf portion at one end adapted to support the blunt end of said iron, the other end portion of said plate being slotted at right angles to said shelf, and adapted to receive said button to hold said iron stand on said rack.

3. A pressing iron holder comprising an iron stand for supporting the pressing iron while in use on the ironing board, and for use in supporting the iron on a wall rack, and a wall rack adapted to be attached to a vertical surface for supporting the pressing iron and the stand during storage, said iron stand comprising a metal base plate shaped to conform to the conventional rounded wedge-shaped pressing surface of the iron, said plate being provided with opposed turned up-and-over contoured flanges adjacent the iron point adapted to engage the shoe of the iron, said base plate being provided with spacing dimples and also with a headed button projecting from the underside of said plate; and said wall rack comprising a back plate with a turned-out shelf portion at one end adapted to support the blunt end of said iron, the other end portion of said plate being slotted at right angles and adapted to receive said button to hold said iron stand on said rack.
